UNITED STATES PATENT OFFICE.

CHARLES G. BLOOMER, OF CRANSTON, AND HENRY F. SANDS, OF PROVIDENCE, RHODE ISLAND.

WINDOW VENTILATOR.

Application filed March 16, 1928. Serial No. 262,194.

Our invention relates to window ventilators of the detachable type.

The essential objects of our invention are to enable the construction of the entire ventilator from thin sheet metal such as aluminum; to positively induce a draft through the room served by the ventilator; to control, modify or shut off either drafts or air currents; to afford a seat for the window sash; to render the use of disk rims unnecessary; and to insure rigidity and strength throughout the entire structure.

To the above ends essentially our invention consists in such parts and in such combinations of parts as fall within the scope of the appended claims.

In the accompanying drawings which form a part of this specification

Figure 1 is a front elevation of our ventilator mounted in an open window,

Figure 2, a rear elevation of the ventilator unmounted, and

Figure 3, a section of the same taken on line 3—3 of Figure 2.

Like reference characters indicate like parts throughout the views.

In the drawings 5 represents the frame and 7 the sash of a window in which our ventilator is shown mounted. The latter comprises an oblong plate or body 9 struck up from thin light weight sheet metal such as aluminum having in its upper margin a rearwardly directed longitudinally disposed shoulder 10, and provided at its top and bottom with oppositely directed longitudinally disposed upper and lower curved flanges 11 and 12. The ends of the plate are rolled over to form upon its forward face cylindrical stiffening columns 13. In this instance auxiliary end plates or sections 14 are slidably mounted upon the ends of the plate 9. In detail each section is formed from a thin metallic sheet with its upper and lower edges loosely contained in flanges 11 and 12, and provided with a marginal shoulder 16 to register with the shoulder 10 of the body 9. Upon its inner edge the material of the section is coiled to form a vertical stiffening column 18. In emergencies the slidable sections may be distended, as herein shown, to fit the device to an excessively broad window opening.

The plate or panel 9 is provided with a plurality, in this instance three, semicircular orifices 20, disposed in longitudinal align-

ment centrally thereof, bounded by outwardly offset peripheral flanges 22. Midway the straight edge of each opening is a curved lug 23 projecting into the opening. Rotatable upon the front face of the panel 9, with their peripheries overlapped by the flanges 22 are three circular metal disks 26, 27 and 28 of the same thickness as the body 9. In this instance the disks are overlapped by guard tongues 30 fixed above the disks upon the back of the panel by rivets 31, while guard tongues 33 cut and bent up from the material of the panel, as at 34, loosely overlap the disk diametrically opposite of the tongues 30 upon the front of the panel.

The disks 26, 27 and 28 are identical in detail and a description of one will serve for all. Each disk has stamped in a semicircular segment of its area a series of transversely disposed inclined or louver fins 36 projecting from the front face of the disk and bounding the louver openings 37. For rotating each disk a tubular shaft 38 is employed provided with a handle 39. Each shaft is journaled in a hole 40 in one of the lugs 23, which hole in each instance extends partially into the plate 9. The shaft end is provided with prongs 41 which extend through openings 42 around the center of the adjacent disk and are clamped thereover.

In operating our device the panel is placed in the open window with the sash 7 resting upon the shoulder 10 as suggested in broken lines in Figure 3. By reason of this shoulder therefore the panel 9 resting upon the sill of the window frame is rigidly held in vertical position. The extension 14 may be employed when necessary and when so used has a shoulder 16 to supplement the shoulder 10 of the panel. The integral terminal columns 13 and 18 upon the panel and extensions insure their respective members against buckling under excessive strain by the sudden descent of the window sash.

It will be observed that the plural character of the rotatable disks not only induces the entrance of fresh air into the room through the louvres and openings in the panel, and permits the escape of foul air from the room, or entirely closes one or all the openings in the panel completely, but that one important function is performed by such plurality of disks which is impossible of attainment by a single disk, as follows. Assuming the wind to be pass-

ing outside the ventilator parallel thereto in the direction of the arrows shown in Figures 1 and 2, the air will strike the edges of the louvers of the disk 28 wherein their edges 36 are disposed in opposition to the direction of the wind. This induces the air to enter the room. Meanwhile the current exterior of the ventilator in continuing its course passes over the backs of the louvers upon the disk 26, since these louvers are inclined in a direction opposite to the direction of disk 28. The passage of the air over the exterior of the louvers of disk 26 exercises a sucking action upon the air in the interior of the room including the air introduced through the disk 28, and thus creates a draft through the room. When this result is sought the louvers of the disk 27 are preferably disposed horizontally as herein shown, in which neutral position the draft is not seriously impeded. If preferred, of course, the louvers of the disk 27 may be disposed in a position diametrically opposite to that shown in the figures, and thus all air may be excluded during the operating of the draft. Various other dispositions of the disks are possible to create the desired varied results in ventilation.

The location of the operating handles at the center of the disks insures a strong and facile operation, and makes unnecessary the increase of parts and expense involved by the use of rotatable auxiliary rims.

We claim:

35 1. In a window ventilator, an oblong plate provided with semicircular orifices longitudi-

dinally disposed therein, disks rotatably supported by the plate over the orifices, and a series of integral forwardly directed louver fins transversely disposed upon semicircular segmental areas of the disks. 40

2. In a widow ventilator, a plate provided with two spaced semicircular orifices extending longitudinally thereof, disks rotatably supported upon the plate registering with the orifices, and forwardly directed integral louver fins integral with semicircular segmental areas of the disks, the fins of one disk being disposed in parallelism with the fins of the other disk and arranged 45 in a vertical direction, and the fins of the first disk being disposed at an inclination opposite to that of the fins of the second disk, whereby a draft is formed between the orifices. 50

3. In a window ventilator, a plate provided with semicircular orifices, integral offset flanges bounding the curved portions of the orifices, lugs upon the plate projecting into the openings midway of their straight 55 portions and provided with holes extending partially into the plate, rotatable shafts extending through the holes, handles upon the shafts, disks upon the shafts overlapped by the flanges, and a series of integral forwardly directed louver fins transversely disposed upon semicircular segmental areas of the disks. 60

In testimony whereof we have affixed our signatures.

CHARLES G. BLOOMER.
